UNITED STATES PATENT OFFICE.

FRITZ ALDENDORFF, OF BERLIN-WILMERSDORF, GERMANY; CHARLOTTE ALDEN-DORFF, HEIRESS OF SAID FRITZ ALDENDORFF, DECEASED.

ELECTROMECHANICALLY-CONTROLLED TELEPHONE SYSTEM.

Application filed January 24, 1925, Serial No. 4,380, and in Germany January 26, 1924.

This invention relates to telephone systems operating with selectors and to selector arrangements for such systems. A feature of the invention consists in an arrangement according to which, after a numerical selection, that is a selecting function controlled by numerical impulses, a non-numerical selection is performed by a selecting device that, in cases in which groups of trunk lines in a bundle of trunks are engaged, jumps over the busy groups and only commences testing the trunks individually in a group containing a free trunk. The function of jumping over busy trunk groups and thereupon testing the trunks individually may take place in the group selecting stage or in the final connecting stage of the connecting function. The numerical and non-numerical selecting functions may each be performed with the aid of several sets or one and the same set of brushes. The numerical and non-numerical selecting functions may furthermore be performed by means of a brush carrier moved longitudinally and then rotated, or the numerical selection may be carried out by turning a brush carrier whereupon the non-numerical selection is accomplished by moving a brush shaft in the direction of its length.

The invention further relates to a selector whose brush carrier executes more than two different kinds of motion. The brush carrier may first move slowly, then quickly and then again more slowly. The first motion of the brush carrier may be a straight line motion and the succeeding motions may be rotary. A further feature of the invention consists in a selector provided with a hollow shaft to which is fixed a ratchet wheel that is locked in its initial position against rotary motion by a stepping pawl, the selector being further provided with a brush carrying shaft adapted to be rotated in the hollow shaft and to be coupled to the ratchet wheel by a coupling member. The coupling of the brush carrying shaft may take place before the ratchet is stepped round.

The invention further relates to a selector whose brush carrier is first moved out of its initial position into an off-normal position and then from the off-normal position back to the initial position by a single spring. The spring is rewound after the brush carrier has been returned to its initial position by a separate rewinding member.

The selector may be provided with a longitudinally movable rod, shaft or the like carrying a tappet which, during the longitudinal return motion of the shaft into its axial normal position, is initially pressed by a spring against a gliding surface and, after the rod has reached the said initial position, the said spring also turns the rod into its radial normal position. The brush carrier may be arranged to perform a slow vertical movement, then a rapid rotary movement and thereupon a slower rotary movement. A further feature of the invention consists in a selector whose brushes are controlled by an electric coupling that receives current impulses through contacts controlled by a cam. After the brushes have been set onto a certain group of contacts the cam wheel is rotated by a stepping wheel until the brushes have reached a desired contact set.

The invention further relates to a group selector provided with brushes which, when they hunt for free trunks, jump over each set of trunks that is busy and only commence testing the trunks individually when they reach a group in which there is still a free trunk. The brush shaft of the group selector may be moved longitudinally and then rotated at a high speed and thereafter at a lower speed. The brush carrier is first moved in one direction with the aid of numerical impulses and then in a second direction under the influence of further numerical impulses before it executes its non-numerical selecting function. The group selector may first be set onto a group of lines under the influence of two series of numerical impulses and then jump over busy sets of trunks in the selected group and thereupon test the trunks individually in the group finally reached. The invention further relates to a connector whose brushes, after being set onto a certain group by being moved in two different directions under the influence of numerical impulses, jump over busy sets of lines in the group finally reached and only then commence testing the lines individually. A further feature of the invention consists in a connector whose brushes are set onto the desired line under the influence of three series of numerical impulses. A further feature of the invention consists in a connector whose brushes first execute long rotary steps and then short rotary steps in being set onto a desired num-

ber and then, on reaching a number comprising several lines, are automatically rotated until they reach a free line leading to the subscriber with several lines. When executing their long steps, for example rotary steps, the brushes may be impelled by a spring.

The invention further relates to a selector whose brushes are rotated continuously at a high speed to the desired contact set where they are stopped by a retracting electromagnet armature. A particularly advantageous effect is attained when the electromagnet is bridged over or arranged to be bridged over by a condenser. The selector may be started and stopped by the same electromagnet. The brushes may be moved by a spring that is wound by a winding magnet. The winding magnet circuit may be controlled by a test relay of the selector. This circuit may be maintained closed during the motion of the selector brushes over the bank contacts of the selector. The circuit of the starting and stopping electromagnet may depend on a bank contact row and the circuit of the rewinding magnet may be controlled during the setting of the brushes by means of a relay and another bank contact row.

The invention relates further to telephone systems with line finders characterized by the fact that their voice current brushes are set upon a calling line by a retracting armature engaging with a tooth of the brush carrier that corresponds to the calling line. The stopping electromagnet of the line finder may be bridged over by a condenser in order to accelerate the falling back of the electromagnet armature.

A further feature of the invention consists in a connector that executes long and short rotary steps and is characterized by the fact that in addition to the customary voice and test contacts, it is provided with bank contacts for subscribers having several lines, these bank contacts being wiped by a brush through which, when a line is engaged, a circuit is closed that causes the rotary magnet to continue rotating the brushes until a free line is found. The long rotary steps of the brushes may be produced by spring power. The circuit of the magnet that controls the long rotary steps may be closed and opened by a contact operated by a cam disk. The contact operated by the cam disk is connected to contacts of the numerical impulse relay.

A further feature of the invention consists, in a telephone system in which the line finders, group selectors and connectors have brushes or wipers which are moved by spring power and whose movements are controlled by an electromagnet without the aid of auxiliary switches. Still another feature of the invention is a telephone system in which switches are employed having wiper

carriers that are moved in two directions and whose wipers are set onto a desired line or trunk by spring power. In a telephone system according to the invention the arrangement is such that a calling party who has been connected through to a numerical switch cannot affect the wipers of the numerical switch until he has sent in at least two numerical impulses. The impulse transmitters or dials of the calling stations are arranged so that when the impulse transmitter is set so as to send one wiper setting impulse into the numerical switch, two impulses are sent over the line to the exchange.

Another feature of the invention consists in a selector with a longitudinally movable rotary shaft that is guided during its longitudinal movement in a stepping wheel, means being provided for preventing it from turning relatively to this wheel.

The invention is shown by way of example in the drawing in which—

Figs. 1-3 illustrate a selector or switch with a longitudinally movable brush carrier (shaft) which, after it has been set relatively to a certain row of bank contacts, is first caused to execute a large step or steps at a high speed under the influence of a spring, and thereupon executes short rotary steps.

Fig. 2 is a plan view of a cam disc and brush that rotates with the brush carrying shaft.

Fig. 3 is a plan view of a stepping wheel provided with a coupling member and

Fig. 4 is a section on the line IV-IV of the brush shaft as seen from above.

Fig. 5 shows the circuits of a line finder, Fig. 6 illustrates a group selector,

Fig. 7 a connector and Fig. 8 shows a modified group selector.

Fig. 9 shows circuits by which a numerical impulse receiver (group selector, connector) is prevented from being affected by a calling line connected to it until at least two numerical impulses have been sent by the calling party through the impulse relay.

Fig. 10 to 12 illustrated details of the shaft locking mechanism.

Fig. 13 is a detail view of the cam operated springs with the operating cam in normal position.

The selector shown in Fig. 1 comprises a shaft 1 which carries brushes 2, only one brush being shown. The shaft 1 is adapted to be shifted longitudinally in a bushing 3 attached to a cam disc 4 (see also Fig. 2). The bushing 3 has a pin 5 along which a groove 6 in the shaft 1 slides so that the shaft 1 can move longitudinally in the cam disc 4 but cannot be turned relatively thereto. The bushing 3 is journaled in another bushing 7 to whose upper end a toothed wheel or stepping wheel 8 is attached. Pivotated to the stepping wheel 8 by a pin 10 is

an armature or coupling member 9. The upwardly extending part 11 of the coupling member protrudes, when the selector is in its normal position, through a slot 13 of the stepping wheel and into a slot 12 of the cam disc 4. In this position of the coupling member a locking member 15 pivoted at 14 is lifted out of the slot 12. The locking member 15 is arranged so that when the 10 cam disc 4 is turned it can only drop into the slot 12 but not into the narrower slots 16' . . . 16".

The bushing or sleeve 7 has an external thread onto which is screwed a cylindrical magnet 17. This magnet can be adjusted upwardly and downwardly by its being turned on the said thread and it is locked in its proper position by a lock nut 18. Screwed onto the bottom and on the thread 20 of the sleeve 7 is a nut 19 with an internal shoulder. This nut rests upon the lower bearing 20 which thus supports the sleeve and the cylindrical magnet 17. Connected to the bottom end of the sleeve 7 is a spring 25 box 21 one end of whose spring 22 is attached to the sleeve 3 whilst its other end is attached to the box 21 and through this box to the sleeve 7. When the selector is addressed or in its normal position the spring 30 22 is wound up and the sleeve 7 is locked against rotation in the direction of the arrow 23 by a detent that engages with the wheel 8. The inner sleeve 3 and the shaft 1 longitudinally displaceable in the same is 35 locked against rotation in the direction opposite to the arrow 23 by the clutch 11 of the coupling member 9.

When current impulses are sent through the lifting magnet 24 the brush shaft 1 is 40 lifted step-by-step and held in its raised position by the holding pawl 26. After the brush shaft has been raised to the desired height its rotation is brought about by excitation of the cylindrical magnet 21 which 45 pulls the armature 9 with the clutch 11 downwardly and thus liberates the cam disc 4 so that this latter is turned by the spring box until the clutch 11 is released by the magnet 14 and permitted to enter a slot in the cam disc, say 16'. The de-energization 50 of the coupling magnet 17 preferably takes place as soon as the advancing edge of the slot reaches the front edge of the clutch 11 so as to give the latter sufficient time to enter the slot 16', even if the cam disc is rotated very quickly. After the cam disc 4 55 has been coupled with the wheel 8 current impulses are sent through the rotary magnet 27 and this turns the wheel and therefore also the cam disc 4 and also the brush shaft 1 step-by-step until the brushes 3 have 60 reached the desired set of bank contacts. The locking member 15 will now be lying on the top surface of the cam disc 4. To 65 return the brush shaft into its initial posi-

tion, the magnet 17 is again energized to withdraw the clutch 11 from the slot in the cam disc. The spring box now rotates the sleeve 3 with the cam disc 4 and the shaft with its brushes in the same direction as before until a pin 28 at the bottom end of the shaft strikes against a slide way 29 placed near the shaft. In this radial position of the shaft the holding pawl 27 will register with the channel 30 of the toothed section 31 of the shaft and the latter will now drop until the pin 28 leaves the slideway 29, whereupon the spring box will turn the shaft further around until it is stopped by the locking member 15 dropping into the broad slot 12 of the cam disc 4. Finally the magnet 17 is de-energized so that the clutch 11 enters the slot 12 and pushes the locking member 15 out of the cam disc. When the locking member is thus lifted a leaf spring 15' (Figs. 10, 11, 12) moves towards the right (Fig. 11) so that when the clutch 11 is again pulled down by the magnet 17 the spring 15' will rest upon the top surface of the cam disc 4 and prevent the locking member from entering the same until it has executed almost an entire revolution that is until the wide slot 12 (Fig. 2) again reaches the locking member.

The cam disc 14 in a connector is provided with ten projections 32. In a group selector, Fig. 6, whose brushes only perform a non-numerical selection, during their rotation the cam disc has only a single projection 32', but in a group selector whose brushes also perform a numerical selection during their rotation there are several projections 32", 32'" on the cam disc. In cases in which the group selector, after executing a numerical selection during its rotary movement, jumps past groups of engaged lines, it is provided with stepped projections 32" etc. as shown in Fig. 8.

The line finder shown in Fig. 5 has a brush carrier which is also arranged to be rotated by a spring 100. The brush carrier is normally locked and when it is unlocked the brushes are whirled round by the spring without stopping until they reach the bank contact set of the calling subscriber.

The further details of the operation of the various switches or selectors will appear more fully hereinafter in the description of the functions which take place in the establishment of a connection between a calling 110 subscriber and called subscriber.

It will be assumed that a telephone system comprises line finders, Fig. 5, group selectors, Fig. 6 and connectors, Fig. 7, each bank contact row of the selectors having 20-50 115 outgoing circuits or trunks while each bank contact row of the connectors in each connector has contact sets connected to 50 subscribers' lines. The connectors are arranged so that when their brushes are set onto a 120 125 130

subscriber who has a plurality of exchange lines the connector will hunt automatically for a free line.

The selectors are adapted to receive one series of numerical impulses and the connectors receive series of numerical impulses.

Assume that a connection is to be made with a subscriber having several exchange lines and whose number is No. 2331. When the calling subscriber raises his receiver a current flows from the positive pole through the line relay 102, contact 103 of the cut-off relay 104, wire 105, sub-station 101, wire 106, contact 107 to the negative pole. The line relay is energized and by opening its contact 108 designates the bank contact set of the calling subscriber, i. e. this contact set is designated by removing the positive potential from the designating contact 109. At the same time the relay 111 of the trunk finder V^1 is energized by a current through the contact 110 so that the contacts 113, 114 are opened and contact 115 is closed. A current now flows from the positive pole through 115, brush 116, off-normal contact 117, starting magnet 118 to the negative pole. The magnet 118 attracts its armature 120 which is pivoted at 119 and thus releases the wheel 121 thus permitting it to be whirled round by the spring 100 at a high speed together with the brushes 122, 123, 124 and 125. As soon as the brush carrier or the wheel 121 leaves its normal position the off-normal contact 117 is opened and the other off-normal contacts 126, 127 are closed. The magnet 118 now receives current through the bank contacts 128, 129 belonging to non-calling lines or busy lines, these contacts being connected to the positive pole through relay contacts which correspond to 108. As soon as the contact set 109 of the calling line is reached by the brush 122 the magnet 118 is deenergized. The designating contacts 109 etc. are displaced relatively to their associated bank contact sets in a direction opposite to the direction of rotation by the brushes. The falling back of the armature of the magnet 118 is accelerated by the condenser 130 connected in parallel to the magnet so that the pawl 120 engages with the wheel 121 and stops the brushes 123, 124, 125 on the contacts 131, 132, 133 and the relay 140 is energized by a current flowing from the positive pole through contact 115 of the relay 111, 116, 140, 123, 131, cut-off relay 104 to the negative pole. The relay 140 opens the contact 141 and closes contacts 143, 144. If the brushes 122, 123, 124, 125 should have overslept the contact set 109, 131, 132, 133 of the calling subscriber, the rotary magnet 154 will receive current impulses that flow from the positive pole through contacts 126, 145, 141, contact 146, interrupter 147 to the negative pole. The magnet 154 then steps the brush carrier 121 backward until the

brush 123 reaches the contact 131 and the relay 140 is energized. The circuit of the stepping magnet 145 is then opened at contact 141.

The calling subscriber is now connected through the brushes 124, 125, contacts 143, 144, contacts 203, 204 (Fig. 6), with the impulse relay 205 so that this latter receives current that flows through the contacts 203, 204, 143, 144, brushes 124, 125, over the subscribers' line 105, 106. The impulse relay closes its contacts 206, 207 and a circuit is closed extending through 206, release relay 208, resistance 209 to the positive pole so that the release relay opens its contact 210 and closes the contacts 211, 212. By the closure of the contact 211 the positive pole of the battery is connected through contact 142 directly to the low resistance winding 114' of relay 140, whereby the contact 131 and the other corresponding contacts of the other line finders of the same group are rendered busy. The closure of contact 211 also results in the energization of relay 150. This relay closes at its contact 151 a locking circuit for itself that extends through contact 126 and at its contact 152 it also disconnects the magnet 118 of the line finder from the brush 122. The energization of the relays 208, 140 and 104 takes place practically at the same moment and by the energization of the relay 104 the line relay 102 is cut off and thereby caused to open the circuit of the relay 111 at contact 110. This results in the closure of armature contact 114 and the magnet 153 now receives a current impulse which flows from the negative pole through the interrupter 154, 114, 153, bank contact 154, off-normal contact 156 to the positive pole. The impulse sent through the magnet 153 results in the wipers 155, 116, 156 being rotated to the next bank contact set 157, 158, 159. If this contact set also leads to a busy trunk the magnet 153 receives another impulse which steps the wipers of the trunk finder 112 further around. This stepping function continues until the brush 155 reaches a wire that is not connected through a contact 126 to the positive pole, i. e. which belongs to a free trunk. This free trunk is then used by the next caller. The calling subscriber sends in two numerical impulses which result in the armature of the impulse relay dropping back twice, so as to send two impulses from the negative pole through 212, 213, 214, lifting magnet 1 to the positive pole. The brush shaft with the brushes 215, 216, 217, 218 is thus lifted two steps. At the first step the vertical off-normal switch 219 is closed. After the two numerical impulses have been sent in the armature of the impulse relay 205 remains attracted and keeps the contact 207 closed for an extended interval thus 130

short-circuiting the winding of the change-over relay 220 for a comparatively long period so that this relay allows its armature to drop back so as to close the contact 221 which results in the relay 222 being energized by a current that flows from the negative pole through 221, 222, 219 to the positive pole. The relay 222 then opens its contact 214 and closes contact 223 to energize the uncoupling magnet 2 by a current that flows from the negative pole through 223, magnet 2, relay contact 224, off-normal contact 225 to the positive pole. The brush shaft which is similar to 1, Fig. 1, with the cam disc 226 (similar to 4, Fig. 1) is now uncoupled from the stepping wheel (similar to 8, Fig. 1) so that the spring box turns the shaft with its brushes and the cam disc out of its rotary normal position. As soon as the shaft leaves this position the contact 225 is opened and contacts 227, 228 of the off-normal switch 234 are closed. If all of the trunks connected to the bank contact sets in the arc 235 are engaged, relays which belong to these trunks will close a chain of contacts 230, 231, 232, 233 and keep the uncoupling magnet 2 energized by a current that flows from the positive pole through the contacts 230 to 233, contact 229 that is closed by the projection 32 of the cam disc as soon as the brushes commence rotating, 224, 2, 223 to the negative pole. When the brushes reach the first set of contacts 235, 236, 237, 238 the spring 239 leaves the projection or cam 32' and the contact 229 is thus momentarily opened to effect a short interruption of the current flowing through the uncoupling magnet 2. This short interruption does not, however, suffice to enable the armature of the uncoupling magnet 2 to fall back so that the brushes are rotated further by the spring box and the brush 218 wipes over the arcuate contact 240. Assuming that all the trunks connected to the bank contact sets of the arc 241 are busy so that the arcuate contact 240 will be connected by a chain of relay contacts to the positive pole and the uncoupling magnet will continue to receive current through the brush 218 and 224, 2, 223, the wipers will be rotated further and the brush 218 will reach the arcuate contact 242. Assuming further that the trunk 243, 244, 245 emanating from the arc 246 is free, the arcuate contact 242 will be disconnected from the positive pole and when the brush 218 reaches the arcuate contact 242 the uncoupling magnet 2 will be de-energized so that the clutch will enter into one of the openings in the cam disc 226 and stop the brush shaft so as to arrest the set of brushes on the contact set 248, 249, 250, 251. The relay 252 will now be energized in a circuit extending from the positive pole through 227, wire 258, contact 248, brush 218, contact 224, magnet 2, contact 223 to the negative pole. The relay 252 at its contact 254 closes a locking circuit for itself and by its contact 255 it prepares a circuit for the uncoupling magnet 2. At its contact 256 it closes the circuit of the stepping magnet 3, which magnet now receives impulses flowing from the negative pole through the interrupter 258, contact 257, contact 256, magnet 3 to the positive pole. The brushes 215, 216, 217, 218 are now turned step-by-step until they reach a bank contact set in the arc 246 which is connected to a free trunk. On their reaching a free trunk for example 243, 244, 245, a current flows from the negative pole through 212, test relay 259, test brush 217, test wire 245, vertical off-normal contact 203 of the idle connector, resistance 302 to the positive pole. A test relay 259 is energized and at its contact 260 short-circuits a part of its winding, while opening the circuit of the rotary magnet 3 at contact 257 and closing the circuit of the auxiliary relay 262 at contact 261 which results in the conductors 263, 264, that extend to the calling subscriber being connected through by the contacts 265, 266 to the impulse relay 305 of the connector, Fig. 7. The impulse relay 305 closes its contact 306, 307 and opens its contacts 308, 309. By the closure of contact 306 the release relay 310 is energized in a circuit extending from the negative pole 306, 310, 311 to the positive pole. The release relay closes its contact 312 that belongs to a chain of contacts which, when all the similar contacts belonging to other trunks or connectors of the same group are closed renders the trunk group busy. The release relay also closes contact 313 which establishes a connection between the test wire 245 and resistance 302 and the positive pole that is independent of the contact 301. It also closes contacts 314, 315 and opens the contacts 316, 317. The calling subscriber now sends in three hundred impulses thus causing three closures of the contact 309 in quick succession so that three impulses flow from the negative pole through 315, 309, 318, lifting magnet 41 to the positive pole. The brush shaft is thus lifted three steps. In the interval ensuing after the series of impulses the changeover relay 319, which was energized during the series of impulses by a current flowing from the negative pole through 315, 319, resistance 320 to the positive pole, is de-energized to close the contact 320 and energize the relay 322 by a current flowing from the negative pole through off-normal contact 323, left hand winding of 322, 321 to the positive pole. The relay 222 closes a locking circuit for itself through contact 324 and at contact 225 prepares a circuit for the uncoupling magnet 2. The calling subscriber now sends in three

tens impulses. At the first tens impulse the uncoupling magnet 2 is energized by a current flowing from the negative pole through 315, 309, 325, 326, contact 327, uncoupling magnet 2 to the positive pole. The uncoupling magnet uncouples the cam disc 328 and the brush shaft from the stepping wheel (similar to 8, Fig. 1) so that the cam disc 328 is rotated together with the brushes 329, 330, 331, 332. As soon as the cam 333 leaves the contact spring 334 the current through the uncoupling magnet 2 will be interrupted even if the impulse through contact 309, 325 has not ceased at that moment so that the clutch will enter an opening in the cam disc 328 and stop the brushes 329 to 332 as soon as they reach the bank contact set 335 to 338. The contact 344 is now pressed by the cam 339 against the contact 327 and the next tens impulse flows from the negative pole through 315, 309, 325, 394, 327, uncoupling magnet 2 to the positive pole. The cam disc is then rotated another step and the clutch enters another opening of the cam disc and stops it when the next cam 340 reaches the spring 334. The third tens impulse now energizes the uncoupling magnet a third time whereupon the clutch enters the next hole in the cam disc and stops the brush 329 to 332 on the bank contact set 341, 342, 343, 344. It is to be noted that the spring which rotates the cam disc with the brushes is adapted to turn the brushes at a speed at which they will always reach the next. The cam next to the one engaging with the contact spring will always reach the spring in the interval between two tens impulses. On the other hand the tens impulses follow one another so quickly that a single retraction of the armature of the impulse relay 305 will never send more than one impulse through the contact spring 334 while it is engaged by one and the same cam on the cam disc.

In the interval ensuing after the series of tens impulses the changeover relay 319 is again de-energized by its being short-circuited at contact 307 and the relay 345 is energized by a current flowing from the positive pole through 346, 345, 347, contact 348 which is closed at the initial rotary movement of the cam disc 328 to the negative pole. The relay 345 closes its contacts 348, 349, 350. By contact 348 a circuit is prepared for the relay 351 which is closed when the changeover relay 319 is energized when the units impulses commence coming in. The relay 351 closes at its contact 352 a locking circuit that extends through the contact 314.

When the units impulses are sent in current impulses flow from the negative pole through 315, 309, 350, rotary magnet 3, off-normal contact 353 to the positive pole. The brushes are hereby stepped round and as,

in the case under consideration, the subscriber No. 2331, who has several lines, is being selected the brushes will be rotated one step so as to be set onto the bank contact set 354, 355, 356, 357. It will be assumed that the subscribers' first line is engaged, this being so the rotary magnet 3 will receive further impulses for the following reason: When the changeover relay is de-energized after the units impulses, or in this case the one units impulse, have been sent in the positive pole is connected through 346, contact 358 to the test relay 359. If the line is engaged the test relay 359 will not be energized. Therefore a relay 360 is energized by a current that flows from the positive pole through 346, 358, contact 361, relay 360, brush 332, contact 354 to the negative pole. The rotary magnet 3 now receives impulses that flow from the positive pole through 353, 3, contact 362, contact 363, contact 364, interrupter 365 to the negative pole. The brushes are thus rotated further step-by-step until a free line is reached when the relay 359 will be de-energized so that the relay 360 will also be de-energized by the opening by the contact 361. The bank contact sets that belong to a subscriber who has several lines lie next to each other in the contact bank and the contact wiped by the brush 332 in the last bank contact set of the group is not connected to the negative pole like the other contacts which are similar to contact 354 so that the relay 360 will be de-energized to open the circuit of the rotary magnet 3 when the brushes reach the last line of the group even if this last line is also engaged.

When a free line belonging to the called subscriber is reached the test relay 359 is energized by a current that flows from the positive pole through 346, 358, 359, test brush 351, test bank contact, cut-off relay of the free line found, to the negative pole. The test relay 359 opens the contacts 361, 363, and closes the contacts 371, 372, 373. By the contact 373 the circuit of the ringing relay 374 is closed and it periodically closes the contacts 375, 376 so that the ringing current generator 377 sends ringing current to the called line. When the called subscriber responds the relay 378 is energized to open the circuit of the ringing relay 374 at contact 379. The relay 378 closes at its contact 380 the circuit of a relay 381 which closes a locking circuit for itself at contact 382 and at its contact 383 prepares a connection between the contact 384 or the negative pole and the right hand end of the winding of the release relay 310. When the called subscriber replaces his receiver the relay 378 allows its armature to drop back so that the release relay 310 is short-circuited through 384, 383. The armature of the release relay then drops back and at contact 314 opens

the locking circuits of the relays 351, 322 and 381. The relay 351 opens the circuit of the test relay 359 at contact 358. On the de-energization of the release relay a circuit 5 is closed at contact 316 which extends from the negative pole through 316, 385, uncoupling magnet 2 to the positive pole. The clutch is then attracted by the magnet 2 and the spring box now turns the cam disc 328 and the brushes further around until the 10 pin, like 28 (Fig. 1) strikes against a stop or slideway like 29 (Fig. 9). The rotation of the shaft is thus stopped with the groove 30 registering with the holding pawl 26, Fig. 4. 15 The shaft and the brushes now drop into their lowest position, and in this position the pin 28 can be rotated past the stop or slide way 29. The spring box therefore turns the shaft further around until the 20 locking member 15 (Figs. 1, 10, 11 and 12) drops into the wide opening 12 (Fig. 2) and finally stops the shaft. The brushes will now be positioned relatively to the contact bank as shown in Fig. 2 and the shaft with 25 the cam disc 328 will be in its normal position so that a recess 328² of a cam 328¹ attached to the cam disc 328 will register with the bent end 353' of the contact spring 353. The spring 353 is, however, as yet prevented 30 from dropping into the recess 328² because a further cam 328⁴ connected with the toothed wheel 8, Fig. 1, has not returned to its normal position. But when this wheel is also restored a recess 328³ will be in line 35 with the recess 328² and allow the contact spring 353 to move into its normal position. The restoration of the stepping wheel 8 is effected by the rotary magnet 3 which on the de-energization of the release relay 310 receives 40 current impulses which flow from the negative pole through the interrupter 365, contact 317, rotary magnet 3, contact 353 to the positive pole. While the uncoupling magnet 2 is energized the wheel 8 is now turned by the rotary magnet 3 until the spring in the spring box is fully rewound and when this is the case the recess 328³ of the cam 328⁴ connected to the wheel 8 will be in line with the recess 328² so that the 45 bent end 353¹ of the spring 353 will drop into the two recesses 328², 328³ so as to open the circuits of the uncoupling magnet 2 and the rotary magnet 3. The connector is thus restored to its normal position in which the 50 spring of the spring box is completely wound up.

If the calling subscriber is first to hang up the release relay circuit 310 is opened at contact 308 of the impulse relay 305 and the 55 restoring operations already described are thus initiated.

On the de-energization of the release relay 310 the current flowing through the test wire 245 and the test relay 259, Fig. 6, is interrupted at contact 313 so that the test

relay 259 allows its armature to drop back. As the calling subscriber has replaced his receiver the impulse relay 205 is de-energized and the release relay 201 is short-circuited by the contacts 280, 281. The release 70 relay will therefore have closed its contact 210 and thus completed the circuit of the uncoupling magnet 2 which extends from the positive pole through 210, 228, 255, 2, 223 to the negative pole of the battery. 75 The spring box turns the brush shaft until its pin (similar to 28, Fig. 1) strikes against the stop 29 and the channel 30 registers with the holding pawl 226. The brush shaft then drops until the pin 28, Fig. 1 is out of the 80 reach of the stop or slide way 29 whereupon the spring (22, Fig. 1) imparts an additional small rotary movement to the shaft to enable the holding pawl 26 to engage with the circular teeth 31. When the shaft 85 has reached its bottom position it opens the locking circuit of the relay 229 by the contact 29. On the de-energization of the test relay 259 the circuit of the rotary magnet 3 was closed at contact 257 and the rotary 90 magnet is thus caused to operate until the stepping wheel (like 8, Fig. 1) of the selector is turned into its initial position so as to fully rewind the spring box. When the cam disc 226 and the stepping wheel 95 have both reached their normal positions the switch 234 moves into its normal position and at contact 227 opens the locking circuit of the relay 252 which is de-energized and opens the rotary magnet circuit 100 at contact 226. The group selector is thus restored to its normal position in which the uncoupling magnet 2 is de-energized and the locking member 15 is lifted out of the wide opening of the cam disc. By the opening of contact 211 at the de-energization of relay 208 the locking circuit of relay 140 of the line finder, Fig. 5, is broken so that relay 140 allows its armature to drop back so as to close at contact 141 a circuit for the rewinding magnet 145 which extends from the negative pole through the interrupter 147, contact 146, 141, 145, 126 to the positive pole. The rewinding magnet 145 now turns the wheel 121 until the spring 100 is wound up and the switch 190 is returned to its normal position by the cam 191. All parts which were engaged in the established connection have now been returned to their 110 initial or normal positions. 115

Fig. 6 illustrates a group selector in which numerical impulses only affect the longitudinal movement of the brush shaft.

Fig. 8 shows a group selector whose numerical selecting functions are controlled by two series of numerical impulses. The first series effects the raising of the brush shaft and the second series causes the shaft to execute long rotary steps. When the last long numerically controlled rotary step has 125 130

tact 480, 463 to the negative pole. The shaft is then rotated by the spring box until its pin (like 28, Fig. 1) strikes a stop 29 in the shape of the slideway, whereupon the shaft 6 first drops and is then given an additional short turn to restore the brushes to their initial position. At the same time a circuit including the rotary magnet 475 is closed which extends from the negative pole 10 through 477, 482, 481, 483, 475 to the positive pole. The rotary magnet 475 now receives impulses until the spring box is completely wound up and the toothed wheel (like 8, Fig. 1) is returned to its initial position. 15 As soon as this is the case the contact 463 is opened to de-energize the relay 462 which results in the circuit of the uncoupling magnet 423 being opened at contact 463 and in the circuit of the rotary magnet 475 being opened at contact 483. The group 20 selector has now been restored to its normal position.

Fig. 9 shows circuits by which, in cases in which a calling party who has been connected through to a group selector hangs up his receiver without sending in numerical impulses, any movement of the group selector is prevented from taking place. The circuit in Fig. 9 is arranged so that the 25 first operating magnet 500 that receives numerical impulses will only receive an impulse if at least two impulses are sent in, the first of these two impulses taking no effect on the operating magnet.

The operation of the circuit is as follows: When a calling party is connected through to the selector the impulse relay 405 attracts its armature and contact 506 closes the circuit of the release relay 507 which extends 40 from the negative pole through 506, 507, 508 to the positive pole. The relay 507 closes contact 509 and thus prepares a circuit for a relay 510. The changeover relay 511 is not energized at the first energization of the 45 impulse relay 505 because contact 512 short-circuits the relay 511. When a series of numerical impulses is sent in the first interruption of the current through 505 results in the opening of the short-circuit of the 50 relay 511 at contact 512. The relay 511 is energized and at its contact 513 prepares a circuit for the relay 510 which is closed at contact 514 when the relay 510 is energized on the first de-energization of the relay 505. 55 The relay 510 being now energized in the circuit extending from the negative pole through 514, 513, 509 to the positive pole now keeps itself locked through its contact 515 and when the next interruption of the 60 current flowing through the relay 505 occurs which is caused by the second numerical impulse, the first operating magnet 500 of the group selector receives an impulse that flows from the negative pole through 518, 519, 517, 65 520, 500 to the positive pole.

When the circuits of the group selector or connector are arranged in this manner a subscriber who is connected through to the selector or connector and who abandons the connection without working his dial will 70 only cause a brief energization of the relay 511 to take place by the dropping back of the relay 505. The relays 511, 507 immediately drop back again without any movements of the selector or connector having 75 taken place.

As regards the construction of the switches it is to be noted that panel type contact banks can be used in which the selecting of the division of bank contact sets 80 desired for the connection is effected by a rotary motion instead of a vertical motion. In this modification the brush carrier would execute a switch straight line trunk hunting motion followed by a slower trunk hunting 85 motion.

The numerical impulse receivers may be divided up into a selector for the numerical selecting function (that is a switch that receives the numerical impulses) which selects 90 a high speed non-numerically controlled switch that first moves at a high speed and then at a lower speed.

I claim:—

1. In a telephone exchange system, a plurality of groups of lines, a selector switch having wipers cooperating with said lines, means for rendering said lines busy, a device for producing numerical impulses, means in said selector operable in accordance with 95 numerical impulses produced for causing said wipers to select a certain group of lines, means responsive to the busy condition of all the lines in said group for causing said wipers in a continuous motion to pass over the lines in said group, a wiper carrier provided with arresting surfaces, an arresting member adapted to cooperate with a said surface for stopping said wipers after they have passed over the last busy line in said 100 group, and means operable thereupon for actuating said wipers to select an idle line in another group. 105

2. A telephone exchange system according to claim 1, characterized in this that means 115 are provided in said selector switch responsive to two successive group-designating numerical impulses.

3. A telephone exchange system according to claim 1, characterized in this that the 120 switch is provided with two sets of wipers, one for performing the non-numerical, and the other for performing the numerical function.

4. A telephone exchange system according 125 to claim 1, characterized by a carrier on which said wipers are mounted, said brush carrier being rotated in response to numerical impulses and longitudinally moved during the line selecting operation. 130

5. In a telephone exchange system, a plurality of lines divided into groups, a selector switch having wipers cooperating with said lines, means for rendering said lines busy, a 5 numerical impulse-producing device, means responsive to the operation of said device for moving said wipers at a low rate of speed to select a certain group of lines, means responsive to the busy condition of 10 all the lines in said group for moving said wipers at a relatively high rate of speed over the lines in said group and into operative relation with the lines in another group, a wiper carrier provided with arresting surfaces, 15 an arresting member adapted to cooperate with a said surface for stopping said wipers after they have passed over the last line of a busy group, and means operable thereupon for moving said wipers at a relatively 20 low rate of speed to select an idle line in the last mentioned group.

6. In a telephone exchange system, a plurality of lines divided into groups, means for rendering said lines busy, a selector having 25 wipers cooperating with said lines, a numerical impulse-producing device, means responsive to the operation of said device for operating said selector to move its wipers in a vertical direction into cooperative 30 relation with a certain group of lines, means responsive to the busy condition of all the lines in said group for moving said wipers in a rotary direction and at a relatively 35 high rate of speed past all the lines in said group, and means operative thereupon for rotating said wipers at a relatively low rate of speed into contact with an idle line in another group.

7. In a telephone exchange system, a plurality of lines, a selector switch having 40 wipers cooperating with said lines, a calling line, a numerical calling device associated with said line, means for variably operating

said selector switch in accordance with said numerical calling device to move with its 45 wipers onto a certain line, means for operatively associating said calling line with said selector switch only after the operation of said device in accordance with at least a series of two impulses, a power device for 50 moving said wipers, a wiper carrier provided with arresting surfaces and an arresting member adapted to cooperate with a said surface for stopping said wipers.

8. In a telephone exchange system, a plurality of groups of lines, a selector switch having brushes for connecting with said lines, a line finder with wipers for connecting 55 said selector switch to a calling line, means for moving said wipers in a continuous motion until they reach a calling line, a toothed member adapted to move with said wipers, a wiper stopping member which engages a tooth of acid toothed member to stop the line finder wipers on the calling 60 line, an electromagnet for operating said stopping member, means cooperating with said electromagnet for accelerating the stopping action of said stopping member, a device for producing numerical impulses, 65 means in said selector operable in accordance with numerical impulses produced for causing said wipers to select a certain group of lines, means responsive to the busy condition of all the lines in said group for causing 70 said wipers to pass in a continuous motion over the lines in said group, a wiper carrier in the selector switch provided with arresting surfaces, and an arresting member adapted to cooperate with said surface for 75 stopping the selector switch wipers after they have passed over the last busy line in said group.

In testimony whereof I have affixed my signature.

FRITZ ALDENDORFF.
